EDWARD BELLEMARE & ELZEAR BELLEMARE,
MIRROR SUPPORTER.
APPLICATION FILED NOV. 16, 1915.

1,184,304.

Patented May 23, 1916.

THE COLUMBIA PLANOGRAPH CO., WASHINGTON, D. C.

UNITED STATES PATENT OFFICE.

EDWARD BELLEMARE AND ELZEAR BELLEMARE, OF REEDS FERRY, NEW HAMPSHIRE.

MIRROR-SUPPORTER.

1,184,304.

Specification of Letters Patent. Patented May 23, 1916.

Application filed November 16, 1915. Serial No. 61,780.

To all whom it may concern:

Be it known that we, EDWARD BELLEMARE and ELZEAR BELLEMARE, residing at Reeds Ferry, in the county of Hillsborough and 5 State of New Hampshire, have invented a new and Improved Mirror-Supporter, of which the following is a specification.

Our invention is in the nature of an improved appliance for supporting and bracing 10 mirrors, pictures, and the like, that are usually supported at the lower edge adjacent the wall and whose upper ends are held in suspension by wire or other flexible hangers, and our said invention has for its 15 object to provide a means or appliance of the character stated of a simple and inexpensive construction, that can be readily adjusted for mirrors of different heights or widths and which effectively serves its intended 20 purposes.

Our invention consists in the peculiar construction and novel arrangement of parts hereinafter explained, specifically pointed 25 out in the appended claims and illustrated in the accompanying drawing, in which:

Figure 1 is a perspective view of our invention. Fig. 2 is a vertical section thereof, taken substantially on the line 2—2 of Fig. 1, the same being shown applied to 30 a wall and to a mirror. Fig. 3 is a detail horizontal section on the line 3—3 of Fig. 2.

In the practical application of our mirror supporter the same, after the parts have 35 been properly adjusted to suit the size of the mirror, picture or other article to be braced thereby, is held against the wall and the back of the mirror, and the said supporter includes upper and lower transverse 40 strap members 1—2 that have adjustment apertures 10—20 hereinafter again referred to.

4 designates a centrally disposed upright 45 and lower ends are attached to the members 1 and 2 by screws, 5, as shown. The upright 4 includes an upper section that has adjustment holes 40 for receiving screw studs 41—41 which also pass through an elongated 50 slot 43 in the lower section of the upright and receive the winged nuts 6—6 that clamp the upper and lower upright sections to their vertically adjusted position, it being understood that such vertical adjustments 55 provide for readily applying our device for

use in connection with mirrors and the like of different heights.

7—7 designates rest members, one of which projects from each end of the lower cross members 2 and the said members each 60 include a spherical head 70—70, as shown. The rest members 7—7 may be adjustably mounted in any of the adjustment apertures 20—20 in the lower cross member 2.

9 designate U-shaped brackets, one of 65 which is mounted on each end of the upper cross member 1 and each of the said brackets is laterally adjustable on the upper edge, to which it is clamped, at its different lateral adjustments by a winged nut 90 that engages the screw stud 11 held in the desired one of the adjustment apertures 10, projected outwardly from the cross member 1 and which passes through an elongated slot 95 in the bracket 9, as best shown in Fig. 3. 70 Each of the U-shaped brackets 9 also carries a clamp bolt 12 in the outer ends of the side portions 91 thereof and upon each of the said bolts or rods 12 is slidably mounted a second U-shaped bracket 13 which fits 75 between the said portions 91 of the bracket 9, the side portions 13^a of the members 13 have longitudinal slots 13^b for receiving the bolts or rods 12, the latter having winged clamp nuts 14—14 for clamping the brackets 80 13.

15 designates roller bearings, one of which is mounted in the outer end of each of the U-shaped members 13.

From the foregoing description taken in 90 connection with the accompanying drawing, it is thought the complete construction, operation and manner of use and the advantages of our invention will be readily understood.

95 After the parts constituting our supporting device have been adjusted vertically and laterally to suit the space of the mirror or picture to be braced, the said mirror or picture is hung from overhead in the usual 100 manner, as shown in Fig. 2, and when thus hung our improved device is placed back of the mirror engaging the wall and the mirror or picture with the lower member 2 that carries the rest members 7—7 forced down 105 below the lower edge of the mirror so that the said lower edge of the mirror may rest and be supported upon the member 7, it being understood that since the upper roller bearings are supported from the mirror 110

hung from the usual over-head hangers the combined brace and supporting device firmly holds the mirror or picture in a proper position and braced against lateral displacement.

What we claim is:

1. A combined brace and support of the character stated comprising parallel upper and lower members, means connecting the said upper and lower members, and a bearing projected outwardly from each end of the upper and lower members, the bearings on the upper members being laterally adjustable.
- 15 2. A combination brace and support of the character stated, comprising parallel upper and lower wall engaging members and a connection between said members, said connection comprising extensible sections, and means for rigidly securing such sections together in their extended or contracted position, a picture back contact bearing projected outwardly from the upper member and a picture rest bearing member projected outwardly from the lower member, substantially as shown and described.
- 20 3. As a new article, an appliance for bracing and supporting the backs of mirrors, pictures, and the like comprising parallel upper and lower strap metal members, a strap metal member that connects at the opposite ends to the upper and lower parallel members centrally thereof, said connecting member being longitudinally adjustable, a bearing projected outwardly from each end of the upper member, and a bearing projected outwardly from each end of the lower member, said upper bearing members being outwardly and laterally adjustable and means for effecting such adjustment.
- 25 4. As a new article, an appliance for bracing and supporting the backs of mirrors, pictures, and the like comprising parallel upper and lower strap metal members, a strap metal member that connects at the opposite ends to the upper and lower parallel members centrally thereof, said connecting member being longitudinally adjustable, a bearing projected outwardly from each end of the upper member, and a bearing projected outwardly from each end of the lower member, said upper bearing members being outwardly and laterally adjustable and means for effecting such adjustment.
- 30 5. As a new article, an appliance for bracing and supporting the backs of mirrors, pictures, and the like comprising parallel upper and lower strap metal members, a strap metal member that connects at the opposite ends to the upper and lower parallel members centrally thereof, said connecting member being longitudinally adjustable, a bearing projected outwardly from each end of the upper member, and a bearing projected outwardly from each end of the lower member, said upper bearing members being outwardly and laterally adjustable and means for effecting such adjustment, the said means comprising a U-shaped frame, a bolt connection laterally slidable in the said upper member, a frame carrying the said bearing, the said frame being adjustably mounted in the U-shaped frame.
- 35 6. As a new article, an appliance for bracing and supporting the backs of mirrors, pictures, and the like comprising parallel upper and lower strap metal members, a strap metal member that connects at the opposite ends to the upper and lower parallel members centrally thereof, said connecting member being longitudinally adjustable, a bearing projected outwardly from each end of the upper member, and a bearing projected outwardly from each end of the lower member, said upper bearing members being outwardly and laterally adjustable and means for effecting such adjustment.
- 40 7. As a new article, an appliance for bracing and supporting the backs of mirrors, pictures, and the like comprising parallel upper and lower strap metal members, a strap metal member that connects at the opposite ends to the upper and lower parallel members centrally thereof, said connecting member being longitudinally adjustable, a bearing projected outwardly from each end of the upper member, and a bearing projected outwardly from each end of the lower member, said upper bearing members being outwardly and laterally adjustable and means for effecting such adjustment.

Copies of this patent may be obtained for five cents each, by addressing the "Commissioner of Patents, Washington, D. C."
